UNITED STATES PATENT OFFICE

GEORGE R. KELTIE, OF WOONSOCKET, RHODE ISLAND, ASSIGNOR TO AMERICAN WRINGER CO., OF WOONSOCKET, RHODE ISLAND, A CORPORATION OF RHODE ISLAND

SQUEEZE ROLL

Application filed February 11, 1930. Serial No. 427,502.

My invention relates to improvements in wringer or squeeze rolls, particularly wringer rolls of the type adapted for use on power driven wringers.

5 Formerly in hand wringers and in some power wringers iron gears placed on the end of a wringer roll shaft away from the roll have been employed for driving co-acting wringer rolls. These iron or other metal 10 gears have proved, particularly in power driven washing machines, to be particularly noisy and for this reason washing machine and wringer manufacturers have left the gears off of the rolls entirely, depending 15 wholly on the friction between the rolls to turn the driven roll or rolls. When the wringer rolls, however, get covered with soap, they become slippery and the upper roll does not turn all the time, with the result that the 20 wringer rolls will not grip the clothes to draw the clothes therethrough, but the driving roll will merely turn without having tractive force either upon the opposing wringer rolls or the clothes.

25 To overcome this objection, Gustav Jantz in November, 1925, in Patent #1,516,886 patented a wringer roll comprising an expressing section and a tractive section provided with the resiliently yielding protuberances of soft rubber either by roughening the ends of the wringer rolls or by providing soft rubber ribs or bands for the tractive section. In practice, however, this wringer roll of Jantz's has not proved entirely successful in that with the 30 positive drive means of Jantz comprising resiliently yielding protuberances, the rolls have slipped in practice about as badly as the old plain rolls. My invention includes providing the wringer roll with rigid substantially noiseless positive driving gear means preferably made of hard rubber vulcanized to the shaft and also for the purposes of strength preferably vulcanized to the end of the soft 35 rubber cylindrical expressing body section preferably spur gears having the spurs thereof of greater height than the normal diameter of the expressing section and the grooves between the spurs correspondingly less to form 40 at all times as positive a drive as the former

metal spur gears, but substantially noiseless.

These and such other objects of my invention as may hereinafter appear will be best understood from a description of the accompanying drawing which illustrates an embodiment thereof.

In the drawing, Fig. 1 is a diagrammatic side elevation of a portion of a power driven wringer.

Fig. 2 is a perspective view of my improved wringer roll.

Fig. 3 is a fragmentary sectional view partially shown in elevation of one end of my improved wringer roll.

In the drawing, wherein like characters of reference indicate like parts throughout, 10 generally indicates a wringer roll constructed in accordance with the teachings of my invention. Said wringer roll has the shaft 12 preferably constructed of metal or other suitable material and a preferably central cylindrical expressing body section 14 constructed of suitable soft material, usually a soft rubber secured to said shaft 12, preferably by vulcanizing it thereto. In order to provide 15 a positive drive gear means substantially noiseless when in operation, I also secure to said shaft 12 suitable positive drive means such as the spur gear 16 constructed of a material relatively noiseless when in mesh, 20 such as hard rubber or phenol condensation product, and also for purposes of strength preferably also secured to the expressing section 14. Thus any fused plastic material such as rubber or phenol condensation product may be employed and I therefore in the claims employ the words "fused plastic material" as covering either hard rubber or phenol condensation product or their 25 equivalents having the silent running characteristics thereof. Where hard rubber is employed, said hard rubber may be vulcanized to the shaft and also to the end 18 of the expressing section 14. The gear means 16 is provided preferably with the spur teeth 20 normally of a greater height than the radial height of the expressing section 14 and the depressions 22 normally of a lesser height than the radial height of the expressing section 14, so that a positive drive may be in- 30

sured when said gear means 16 is in mesh with similar gear means on an adjacent wringer roll 10. To secure a more positive drive I may provide suitable gear means 16 at each end of the shaft 12 and preferably secured to each end of the central cylindrical expressing section 14.

In Fig. 1 I have shown my improved type of wringer or squeeze roll in use on a power wringer. In this case the lower wringer roll 10^a is positively driven by the means of gearing preferably bevel gears (not shown), through the medium of the vertical shaft 24.

It is obvious that the gear means 16^a on each end of the roll 10^a will intermesh with the gear means 16^b on each end of the upper wringer roll 10^b to secure at all times a positive drive therefor.

My improved wringer roll may be constructed in any suitable manner. Where rubber is employed as both the expressing and driving means therefor a plurality of layers of soft rubber are wound around the shaft 12 as usual and the suitably shaped gear means constructed of hard rubber are suitably slipped on each end of the shaft 12 contacting the body portion of said layers of soft rubber forming the expressing section 14. The entire roll is then vulcanized in the usual manner, thus vulcanizing the layers of rubber together and to the shaft 12 to form the expressing section 14 and to tightly secure the hard rubber gear means to the shaft 12 and also to the ends 18 of the expressing section 14. Any type, however, of an expressing section may be employed and any type of rigid substantially noiseless gear means, such as phenol condensation product or other suitable material may be employed. It is thus apparent that I have provided not only a wringer roll having a relatively soft expressing section and rigid positive drive means for said wringer roll substantially noiseless when in use, but that I have provided in the actual wringer or other machine the combination of two or more such rolls which will operate in use in substantially noiseless fashion.

While my invention is primarily adapted for use in squeeze rolls for wringing machines, it is obvious that it may be employed in any type of a squeeze roll.

It is understood that my invention is not limited to the specific embodiment shown and that various deviations may be made therefrom without departing from the spirit and scope of the appended claims.

What I claim is:

1. A squeeze roll comprising a shaft, a central cylindrical rubber expressing body vulcanized to said shaft, and a hard rubber spur gear having spur teeth of greater height than that of said rubber expressing body vulcanized to said shaft and to the end of said expressing body.

2. A squeeze roll comprising a shaft, a cylindrical rubber expressing body vulcanized to said shaft, and a hard rubber spur gear having spur teeth of greater height than that of said rubber expressing body vulcanized to said shaft.

In testimony whereof I affix my signature.

GEORGE R. KELTIE.
